(57) **CLAIM**

The ornamental design for a display screen with transitional graphical user interface, as shown and described.

DESCRIPTION

FIG. 1 is a front view of a first image in a sequence for a display screen with transitional graphical user interface showing my new design; and,

FIG. 2 is a front view of a second image thereof. The broken line at the periphery of the figures illustrate a display screen, and the remainder of the broken lines illustrate portions of the transitional graphical user interface. None of the broken lines form part of the claimed design.
